UNITED STATES PATENT OFFICE.

WILLIAM G. CAMPBELL, OF PHILADELPHIA, PENNSYLVANIA.

DESIGN FOR AN OUTLET-FITTING FOR PIPE-CONDUITS FOR ELECTRICAL CONDUCTORS.

43,713.

Specification for Design.

Patented Mar. 18, 1913.

Application filed November 16, 1912. Serial No. 731,882. Term of patent 14 years.

To all whom it may concern:

Be it known that I, WILLIAM G. CAMPBELL, a citizen of the United States, residing at Philadelphia, county of Philadelphia, and State of Pennsylvania, have invented a new, original, and ornamental Design for Outlet-Fittings for Pipe-Conduits for Electrical Conductors, of which the following is a specification, reference being had to the accompanying drawings, forming part thereof.

Figure 1 is a perspective view of a terminal fitting embodying my design; and Fig. 2 is a face view of the fitting.

I claim:

The ornamental design for an outlet fitting for pipe conduits for electrical conductors, as shown.

WILLIAM G. CAMPBELL.
